Primary Examiner — Cynthia Ramirez*Assistant Examiner* — Jeremy S. Swartz(74) *Attorney, Agent, or Firm* — VAN COURT & ALDRIDGE LLP(57) **CLAIM**

I claim the ornamental design for a pair of vehicle seats, as shown and described.

DESCRIPTION

FIG. 1 is a top, front, right side perspective view of a pair of vehicle seats of the new design;

FIG. 2 is a top, rear, right side perspective view thereof;

FIG. 3 is a front elevation view thereof;

FIG. 4 is a right side elevation view thereof;

FIG. 5 is a rear elevation view thereof;

FIG. 6 is a left side elevation view thereof; and,

FIG. 7 is a top plan view thereof.

The broken lines in the figures illustrate environment which form no part of the claimed design.

1 Claim, 4 Drawing Sheets(56)
